UNITED STATES PATENT OFFICE.

THEODORE HOSMER, OF SANDUSKY, OHIO.

IMPROVEMENT IN LIFE-PRESERVING FLOATS.

Specification forming part of Letters Patent No. 136,436, dated March 4, 1873.

To all whom it may concern:

Be it known that I, THEODORE HOSMER, of Sandusky, in the county of Erie and State of Ohio, have invented a new and useful Improvement in Life-Preservers, of which the following is a specification:

The invention consists in the improvement of life-preservers, as hereinafter described and claimed.

In the drawing, Figure 1 is a top or plan view. Fig. 2 is a section taken on the line $x x$ of Fig. 1. Fig. 3 is a section taken on the line $y y$ of Fig. 1.

Similar letters of reference indicate corresponding parts.

A is a frame somewhat resembling a horse-shoe in form, made of wood, in two sections, the inner sides of which are grooved, with the groove filled with cork B to make the frame buoyant. The frame may be made of metal, or of any other suitable material, with one or more air-tight chambers therein, for the purpose of making the frame buoyant. The frame is made, say, three feet wide and four feet long, and about three inches in thickness, with a circular orifice, C, therein to receive the weight of the person using it. Through the opening D E is a safety-belt attached to the frame, which is buckled around the chest of the person, under the arms or around the waist. F F are safety-loops for the person using the preserver. G G' are loops, by means of which other persons in the water may hold on to the frame and support themselves without sinking the frame; the frame is, therefore, designed to be of sufficient buoyancy to support one or more persons.

When a person has succeeded in thus fastening himself in the frame he is safe as far as sinking is concerned, and will find

it a real life-preserved; but I do not only desire to keep him and others from sinking, but to give him means for moving or propelling himself while in the water; and for this purpose I make the slots H H through the frame, in which I place the rotating paddles or propellers I I. J is a transverse shaft, to which the propellers are attached. The shaft is revolved by means of the levers K K, which the person in the frame seizes, the power to rotate the shaft being applied when he pulls on the levers by means of ratchet-wheels L L, pawls M M, and spur-wheels N N. This arrangement is seen in Figs. 1 and 2.

It will be observed that in a small structure like a life-preserved it is not only necessary to secure an effective propeller, but that its operative mechanism shall be, as far as possible, protected from the waves, and be arranged to occupy no additional space, when packed, beyond that required for the life-preserved itself. By my invention it will be seen that I do not, therefore, only operate the propeller easily and to advantage, but my actuating mechanism is entirely inclosed within the life-preserved, the whole making a compact and easily-transportable device.

Having thus described my invention, I claim as new and desire to secure by Letters Patent—

The propeller mechanism I J, the ratchet-wheels L, pawls m, spur-wheels N, and levers K, combined and applied in connection with a life-preserved as and for the purpose described.

THEODORE HOSMER.
